GUN ORDER COMPUTER

George A. Crowther, Lawrence S. Brown, and William G. Hampton, Long Island City, N.Y., assignors to Sperry Rand Corporation, Ford Instrument Company Division, Long Island City, N.Y., a corporation of Delaware

Filed Nov. 12, 1957, Ser. No. 697,300
2 Claims. (Cl. 235—61.5)

The present invention relates to an apparatus for converting gun orders derived from the output of the gunfire control computer of a 5"-38 cal. gun to corresponding gun orders for a 3"-50 cal. gun.

In certain types of naval gunfire controls, a gun is controlled on the moving ship from a director which maintains its sights on the target. Various data obtained by the director and from other sources are processed through a computer to obtain orders for the proper firing of the gun. Two of the primary gun orders derived from the computer are the gun elevation order angle $E'g$ which is the ordered angle between the line of bore and its projection on the deck plane and the gun train order angle $B'gr$, which is the ordered angle between the vertical plane through the ship's centerline and the vertical plane through the gun bore axis, measured in the deck plane clockwise from the bow. These orders transmitted to the guns are employed to direct the guns for proper firing.

One object of the present invention is to provide a comparatively simple apparatus for converting the order angles $E'g$ and $B'gr$ derived from the output of the computer of the gunfire control system of a 5"-38 cal. gun to the corresponding gun orders for a 3"-50 cal. gun thereby avoiding the requirement of a separate complicated computer for the 3"-50 cal. gun. A computer for the gun fire control system of a 5"-38 cal. gun is Computer Mark 1A Model 13. The converter embodying this invention does not affect the regular operation of the Computer Mark 1A in its solution of the 5"-38 cal. gun problem.

In accordance with the present invention, increments of gun elevation and gun train respectively are computed by the converter of the present invention to be added to the 5"-38 cal. gun orders calculated in the known manner in a computer to produce corresponding gun orders for the 3"-50 cal. guns. These increments are computed as functions of either the 3"-50 cal. time of flight or the 5"-38 cal. time of flight. Straight line approximations are used extensively in the derivation of the formulas which are the basis of the mechanization. A high degree of correction is avoided to maintain simplicity, minimize the size of the converter mechanism and reduce the amount of components to a minimum.

GLOSSARY OF SYMBOLS

3—pertaining to 3"-50 cal. gun.

5—pertaining to 5"-38 cal. gun.

Δ —increment between 3" and 5" values.

$B'gr$ —gun train order—the angle between the vertical plane through the ship's centerline and the vertical plane through the gun axis measured in the deck plane clockwise from the bow.

dR —rate of change of range.

$E2$ —predicted target elevation or ballistic position angle—the angle between the horizontal plane and the line of fire to the future target position, measured upward from the horizontal plane.

Eb —director elevation angle—the angle between the deck plane and the line of sight measured in the vertical plane through the line of sight upward from the deck plane.

$E'g$ —gun elevation order angle—the angle between the deck plane and the line of fire, measured in the vertical plane through the line of fire. Positive angles are measured upward from the deck plane.

5 ΔIV —change in initial velocity from normal value (value before gun has been fired).

L —level angle—the angle between the deck plane and the horizontal plane measured in the vertical plane through the line of sight—positive when the portion of the deck towards the target is down.

10 RdE —linear elevation rate (knots)—the component of relative velocity of ship and target which is at right angles to the line of sight in the vertical plane containing the line of sight (positive when upward).

15 $RdBs$ —linear bearing rate—the horizontal component of relative velocity of ship and target which is at right angles to the vertical plane containing the line of sight—positive to the right.

Tf —time of flight—the time of flight of the projectile to the predicted or future target position.

20 ΔTf_n —normal difference between $Tf3$ and $Tf5$.

ΔTm —time of flight increment, correction for the time of flight due to difference between the actual velocities of the 5" gun and the 3" gun.

25 $Tf/R2$ —conversion constant (sec./yd.).

Vfn —normal sight angle—the difference between normal gun elevation order angle and director elevation angle.

$$Vfn = E'g - Eb$$

30 Vm —sight angle correction due to change in initial velocity.

Vt —sight angle correction (deg.) due to elevation rate RdE .

35 Zd —cross-level angle—the angle between the vertical plane through the line of sight and the plane perpendicular to the deck plane through the intersection of the deck plane and the vertical plane through the line of sight.

40 Various other objects, features and advantages of the invention are apparent from the following description and from the accompanying drawings, in which

FIG. 1 is a graph showing in full lines the true values derived from the ballistic tables and in dotted lines the assumed values for mechanization of the ΔVm corrections to 3"-50 cal. sight angle for loss of IV at different values of $Tf3$ for different position angles $E2$;

FIG. 2 is a graph showing in full lines the true values derived from the ballistic tables and in dotted lines the assumed values for mechanization of the ΔVfn sight angle correction under normal initial velocity conditions at different values of $Tf5$ for different position angles $E2$;

FIG. 3 is a graph showing in full lines the true values derived from the ballistic tables and in dotted lines the assumed values for mechanization of ΔTf_n at different values of $Tf5$ for different position angles $E2$;

FIG. 4 is a graph showing in full lines the true values derived from the ballistic tables and in dotted lines the assumed values for mechanization of ΔTm corrections to Tf for 100 FSIV loss at different values of Tf for different position angles $E2$;

FIG. 5 is a graph showing in full lines the true values derived from the ballistic tables and in dotted lines the assumed values for mechanization of $Tf3/R2$ for position angle $E2$ of 45° at different values of $Tf3$; and

FIG. 6 is a diagram of a mechanism for obtaining the elevation order angle $E'g$ and the gun train order angle $B'gr$.

Derivation of Formulas

70 The difference between the 5" elevation order angle $E'g5$ and the 3" elevation order angle $E'g3$, which is

also the difference between the 5" sight angle Vs5 and the 3" sight angle Vs3, designated as $\Delta E'g$ is composed of the difference ΔVm in superelevation or sight angle correction due to either the 3" or 5" initial velocity not being normal, the difference ΔVfn in superelevation or sight angle correction under normal initial velocity conditions and the difference ΔVt in superelevation or sight angle correction for the elevation rate of target motion during the interval of $\Delta Tf/R2$. The basic equation to be mechanized designating this relationship is as follows:

$$\Delta E'g = \Delta Vm + \Delta Vfn + \Delta Vt \quad (1)$$

The normal initial projectile velocity is the velocity of a projectile of a gun fired for the first time and this velocity designated as f.s. (feet/sec.) is determined from the usual available ballistic tables for the gun. These tables indicate that the normal initial velocity of a 5"-.38 cal. gun is 2500 f.s. and of a 3"-.50 cal. gun is 2650 f.s. As the gun is fired, it loses initial velocity.

ΔVm is the difference in correction due to either the 3" or 5" initial velocity being other than normal and is shown in the graph of FIG. 1. The differences in correction to sight angle between the 3" ballistics and the 5" ballistics are so slight that they may be considered equal. As shown in the graph of FIG. 1 and as determined empirically therefrom.

$$\begin{aligned} \Delta Vm &= kTf3 \cos (E2+L) \Delta IV \\ \Delta Vm &= .0041Tf3 \cos (E2+L) (\Delta IV5 - \Delta IV3) \end{aligned} \quad (2)$$

For convenience in instrumentation, especially in connection with the potentiometers, so that all plus voltages may be employed, it is desirable to shift the origin of the I.V. scale by substituting for $\Delta IV5$ its equal $(100 - \Delta'IV5)$ and for $\Delta IV3$ its equal $(100 - \Delta'IV3)$. Referring the I.V. scale to 2600 f.s. (ballistic table readings plus 100) for $\Delta IV5$ and 2750 f.s. (ballistic table readings plus 100) for $\Delta IV3$, there is obtained

$$\begin{aligned} \Delta'IV3 &= (2750 - IV3) \\ \Delta'IV5 &= (2600 - IV5) \end{aligned} \quad (3)$$

Substituting in Equation 2 for $\Delta IV5$ and $\Delta IV3$ their respective equals, $100 - (2600 - IV5)$ and $100 - (2750 - IV3)$, there is obtained

$$\begin{aligned} \Delta Vm &= .00041Tf3 \cos (E2+L) \times [100 - (2600 - IV5) - \\ &\quad (100 + 2750 - IV3)] \\ \Delta Vm &= .00041Tf3 \cos (E2+L) \times [(2750 - IV3) - \\ &\quad (2600 - IV5)] \end{aligned} \quad (3)$$

The true values of ΔVfn determined from the ballistic tables and the values approximated therefrom for easy mechanization are plotted in FIG. 2 as functions of

$$\frac{\Delta Vfn}{\cos E 2} + .14$$

in order to minimize the effect of the position angle E2. The best mechanical solution is obtained by mechanizing the equation

$$\Delta Vfn = f(Tfn5)$$

where ΔVfn is the normal correction sight angle at 0° elevation angle E2. Since this expression is a function of 5" normal time of flight, it is affected by changes in the 5" initial velocity and must be corrected. Accordingly,

$$\Delta Vfn = k(f'Tf5 + .000365Tf5\Delta IV5)$$

In the latter equation, k is not a constant but varies. However, for the purposes of 5" correction, an average value of .175 is chosen and for $\Delta IV5$ is substituted its equal $100 - (2600 - IV5)$. Then

$$\Delta Vfn = k(f'Tf5 + .00639Tf5 - .0000639Tf5(2600 - IV5)) \quad (4)$$

In instrumentation, the product of $Tf5$ and $IV5$ must be amplified before being utilized for further instrumenta-

tion. Since the product of $Tf5$ and $IV5$ is employed in connection with other phases of instrumentation herein, as will be described, for the term $.0000639Tf5(2600 - IV5)$ in Equation 4, there is substituted

$$.0000639Tf5(2600 - IV5)$$

to avoid the necessity of an additional amplifying step. The difference between the values of the two terms is insignificant.

10 The best average solution for ΔVfn is obtained by subtracting a constant from ΔVfn

$$\begin{aligned} \Delta Vfn &= (\Delta Vfn - .24) \cos (E2+L) \\ \Delta Vfn &= [f''(Tf5) + .00639Tf5 - .0000639Tf5 \\ &\quad (2600 - IV5) - .24] \times \cos (E2+L) \end{aligned} \quad (5)$$

15 Referring to FIG. 2, it should be noted that the mean average represented by the graph A actually mechanized by the instrumentation of the present invention is offset by the constant vertical increment .24-.14. This graph A is the mean average of the two graphs for $E2=0$ and $E2=70$.

20 The values of $f''(Tf5)$ in Equation 5 for different values of $Tf5$ are indicated in FIG. 2 as determined empirically from the graph therein.

25 The only other correction to sight angle is ΔVt , the correction for the elevation rate of target motion during the interval of $\Delta Tf/R2$.

$$30 \Delta Vt = k'RdE \times \frac{\Delta Tf}{R2} \text{ radians}$$

RdE is measured in knots

$$\frac{\Delta Tf}{R2} \text{ is measured in sec./yards}$$

35 $k' = .563 \text{ yd./sec./knot of target speed} \times 57.2958^\circ/\text{radian}$
 $k' = 32.26$

$$38 \Delta Vt = 32.26RdE \times \frac{\Delta Tf}{R2} \quad (6)$$

40 To determine the quantity $\Delta Tf/R2$ in Equation 6, the true and mechanized values of $Tf/R2$ are plotted against the 3" time of flight in FIG. 5. Since there is no appreciable change in $Tf/R2$ for various position angles $E2$ and being average, the values are plotted only for 45° position angle. Since the predicted values of the 5 inch gun computer are based on the 5" $Tf/R2$, it is necessary to correct only for the difference between the 3" $Tf/R2$ and the 5" $Tf/R2$. This increment of $Tf/R2$ is equal to

$$45 \Delta Tf/R2 = .001110 + .0000665Tf5 \\ + .0000006(2750 - IV5) - \frac{Tf5}{R2} \quad (6a)$$

50 Both the quantity

$$\frac{Tf5}{R2}$$

55 and the quantity

$$\frac{Tf3}{R2}$$

60 have the constant .001110 as a common reference. The 65 constant .001110, therefore, may be eliminated from equation 6a in mechanizing said equation, assuming that the input

$$\frac{Tf5}{R2}$$

70 has had this constant eliminated.

In Equations 3 and 5, the term $Tf5$ is involved and, therefore, it is necessary to determine the value of this term for mechanization.

It is known that

$$Tf3 = Tf5 + \Delta Tf_n + \Delta Tm + .001126dR(Tf3 - Tf5) \quad (7)$$

(Ignoring corrections for wind, air temperature and air density)

ΔTf_n is the difference between the normal 3" time of flight and the normal 5" time of flight and is plotted on the graph of FIG. 3 as a function of the 5" time of flight. From the ballistic tables, the two true value curves for $E2=0^\circ$ and $E2=70^\circ$ indicated in full lines are plotted, and from these two curves, the true value curve representing the mean value of ΔTf_n found to approximate that for an $E2=30^\circ$ is plotted in full lines. From the latter true value curve, the mechanism curve B made up of straight lines is approximated therefrom and this is used to determine the approximate empirical formula used as a basis of instrumentation. Hence:

$$\Delta Tf_n = f'''(Tf5) + .0443Tf5 - .1388 \quad (8)$$

ΔTm is the correction for the time of flight due to difference between the actual initial velocities of the 5" gun and the 3" gun. The I.V. corrections have been plotted in FIG. 4 together with the mechanism values for both the 5" and 3" gun. The 5" I.V. correction is not coincident with the theoretical value as shown by the curve C, and mechanization for ΔTm is, therefore, preferably along said curve, as indicated by the curve D.

Hence, as determined empirically from the graph of FIG. 4

$$\Delta Tm = .000365Tf5\Delta IV5 - .000525Tf3\Delta IV3$$

Since $Tf5$ usually is very nearly equal to $Tf3$, then

$$\Delta Tm = .000365Tf3\Delta IV5 - .000525Tf3\Delta IV3 \quad (9)$$

where ΔIV is considered positive for increasing IV. Substituting $Tf3$ for $Tf5$ will cause a maximum error of .07 second.

Correction for the change in range during the time of flight is expressed in Equation 7 as $.001126dR(Tf3 - Tf5)$, since the 5" time of flight is predicted on the 5" advance range R2. This leaves only the difference between the 3" and the 5" time of flight to be corrected. The constant .001126 is the average $Tf/R2 = .002$ sec./yd. $\times 563$ yd./sec/knot of target speed. An assumption of a fixed dR rate, equal to approximately -450 knots, further simplifies the mechanization, so that Equation 7 may be rewritten as:

$$Tf3 = Tf5 + \Delta Tf_n + \Delta Tm - .510(Tf3 - Tf5) \quad (10)$$

Substituting Equations 8 and 9 into Equation 10

$$Tf3 = Tf5 + .0293Tf5 - .0919 + .662[f'''(Tf5) + .000365Tf3\Delta IV5 - .000525Tf3\Delta IV3] \quad (11)$$

Referring the I.V. scale to 2600 f.s. for IV5 and 2750 f.s. for IV3, for convenience in mechanization as indicated above in connection with other phases of the mechanization, Equation 11 may be rewritten by substituting for $\Delta IV5$ its equal $(100 - \Delta IV3)$ when referred to 2600 f.s. and for $\Delta IV3$ its equal $(100 - \Delta IV5)$ when referred to 2750 f.s. Therefore,

$$\begin{aligned} \Delta IV3 &= (2750 - IV3) \\ \Delta IV5 &= (2600 - IV5) \end{aligned}$$

Rewriting Equation 11 with the substitutions indicated, there is obtained

$$\begin{aligned} Tf3 &= \frac{1.0293Tf5 - .0919 + .662f'''(Tf5)}{1.0106 - .000348(2750 - IV3) + .000242(2600 - IV5)} \\ &= \frac{1.0293Tf5 - .0919 + .662f'''(Tf5)}{1.0106 - .000348(2750 - IV3) + .000242(2600 - IV5)} \quad (12) \end{aligned}$$

The value of $f'''(Tf5)$ is indicated in FIG. 3 for different values of $Tf5$.

The only corrections to gun train orders $B'gr$ are for

(1) Component of target motion perpendicular to line of sight during the difference between the 3" Tf and the 5" Tf .

5 (2) ΔDzs correction in the deck plane for trunnion tilt. The resultant bearing rate due to target and ship's motion is called $RdBs$ and is transmitted from the computer of the 5" gun. This bearing rate when multiplied by $\Delta Tf/R2$ gives the predicted increment of gun train when multiplied by the proper conversion constants and results in the following equation

$$\Delta B'gr = [32.26RdBs \times \Delta Tf/R2 + \Delta Dzs] \frac{1}{\cos(E2+L)} \quad (13)$$

15 No correction ΔVz , i.e. difference in correction to gun elevation to compensate for trunnion tilt, is made to the gun elevation order increment $\Delta E'g$, since it is assumed that the correction supplied by the computer of the 5" gun to its computed gun elevation is sufficient. The converter of the present invention does supply a gun train order correction, which is an approximation of the solution of the 5" gun computer, this solution being represented as follows:

$$\Delta Dzs = 2 \sin Zd \times f(\Delta E'g)$$

Since the inputs to the converter are 5"E'g and 5"B'gr, these do contain the trunnion tilt corrections. This results in the equation

$$\Delta Dzs = 1.22 \sin Zd \Delta E'g \quad (14)$$

Substituting Equation 14 in Equation 13 results in

$$\begin{aligned} \Delta B'gr &= [32.26RdBs \times \Delta Tf/R2 \\ &\quad + 1.22 \sin Zd \Delta E'g] \frac{1}{\cos(E2+L)} \quad (15) \end{aligned}$$

The equations to be mechanized for the values of $\Delta E'g$ and $\Delta B'g$ are summarized as follows:

40 The basic equation for $\Delta E'g$ is

$$\Delta E'g = \Delta Vm + \Delta Vfn + \Delta Vt \quad (1)$$

The components of this basic equation are as follows:

$$\Delta Vm = .00041Tf3 \cos(E2+L) \times [(2750 - IV3) - (2600 - IV5)] \quad (3)$$

$$\Delta Vfn = [f''(Tf5) + .00639Tf5 - .0000639Tf3(2600 - IV5) - .24] \times \cos(E2+L) \quad (5)$$

$$\Delta Vt = 32.26Rde \times \Delta Tf/R2 \quad (6)$$

50 The $Tf3$ for Equations 3 and 5 is as follows:

$$\begin{aligned} Tf3 &= \frac{1.0293Tf5 - .0919 + .662f'''(Tf5)}{1.0106 - .000348(2750 - IV3) + .000242(2600 - IV5)} \\ &= \frac{1.0293Tf5 - .0919 + .662f'''(Tf5)}{1.0106 - .000348(2750 - IV3) + .000242(2600 - IV5)} \quad (12) \end{aligned}$$

The $f'''(Tf5)$ in Equation 12 is determined empirically for the different values of $Tf5$ from the graph of FIG. 3 and these values are as follows:

$$\begin{aligned} 60 f'''(Tf5) &= .0296(Tf5 - 3) \text{ for } Tf5 > 3 < 5.25 \\ &= .1096(Tf5 - 4.64) \text{ for } Tf5 > 5.25 < 8 \\ &= .2192(Tf5 - 6.32) \text{ for } Tf5 > 8 \end{aligned}$$

65 The $f''(Tf5)$ in Equation 5 is determined empirically for the different values of $Tf5$ from the graph of FIG. 2 and these values are as follows:

$$\begin{aligned} f''(Tf5) &= .027(Tf5 - 3) \text{ for } Tf5 > 3 < 5.25 \\ &= .100(Tf5 - 4.64) \text{ for } Tf5 > 5.25 < 8 \\ &= .200(Tf5 - 6.32) \text{ for } Tf5 > 8 \end{aligned}$$

70 $\Delta Tf/R2$ for Equation 6 is as follows:

$$\begin{aligned} \Delta Tf/R2 &= .001110 + .0000665Tf3 \\ &\quad + .0000006(2750 - IV3) - Tf5/R2 \quad (6a) \end{aligned}$$

75 In Equation 6a the constant .001110 is eliminated, assuming that the input $Tf5/R2$ has had this constant eliminated.

The equation for $\Delta B'gr$ is as follows:

$$\Delta B'gr = \left(32.26 R dBs \times \frac{\Delta Tf}{R2} \right) + 1.22 \sin Zd \Delta E'g \frac{1}{\cos(E2+L)} \quad (15)$$

FIG. 6 shows the mechanism for the instrumentation of Equations 1, 3, 6, 12, 6a and 15 to obtain the values of $E'g(3'')$ and $B'gr(3'')$. The inputs necessary to attain these values are

- (1) $Tf(5'')$ ----- 5" time of flight.
- (2) $Tf5/R2$ -----
- (3) I.V. (5'') ----- 5" initial velocity.
- (4) $RdBs$ ----- Bearing rate.
- (5) RdE ----- Elevation rate.
- (6) $E2+L$ ----- Sum of elevation angle $E2$ and level angle L .
- (7) Zd ----- Cross-level angle.
- (8) $E'g(5'')$ ----- 5" gun elevation.
- (9) $B'gr(5'')$ ----- 5" gun train order.
- (10) I.V. 3" ----- 3" Initial velocity.

Inputs 1-9 are obtained from the output of the computer for the gunfire control system of the 5" gun. Input 10 determined from ballistic tables is set by a handcrank 10 (FIG. 6) periodically, as for example, every day, in accordance with the number of rounds of ammunition already fired from the 3" gun.

FIG. 6 shows diagrammatically the converter by which the gun elevation order $E'g$ and the gun train order $B'gr$ for the 5" gun are converted into the corresponding orders for the 3" gun. In this diagram of FIG. 6, the dotted lines represent mechanical motion transmissions and the full lines represent electrical connections for transmitting electrical quantities. The mechanical motion transmitters may represent shafts, and the values of the quantities transmitted thereby are represented by the number of revolutions of these shafts. The electrical connections transmit currents, the voltages of which correspond to the values of the quantities transmitted.

The system of FIG. 6 is composed of components, such as resolvers, potentiometers, adding networks and servo mechanisms, which, per se, are well known. These, therefore, are shown only schematically and referred to briefly.

$Tf3$ is one of the essential quantities required to evaluate the 3" gun orders, and is determined from Equation 12. For the solution of this Equation 12, there are required inputs $Tf5$, $IV3$ and $IV5$, and the determination of $f''(Tf5)$. As indicated in the graph of FIG. 3, the values of $f''(Tf5)$ vary according to the values of $Tf5$. A potentiometer 11 with a mechanical input $Tf5$ derived from the output of the 5" computer is wound to incorporate therein the values of $f''(Tf5)$ for the different values of $Tf5$ according to the graph of FIG. 3, so that the output of this potentiometer will be a voltage corresponding to $f''(Tf5)$. This quantity $f''(Tf5)$ is then transmitted to a resistor adding network 12, the output of which is $-Tf3$ constituting the algebraic sum of the inputs according to Equation 12. An adding network capable of functioning according to the foregoing requirement is described in the June 1947 issue of the publication entitled "Electronic Engineering" on pages 178-180 thereof. A high gain linear amplifier 13 for the output of the adding network 12 provides power amplification which serves to isolate the signal source and load impedance. Since the output of the network and amplifier combination 12 and 13 has a 180 degree phase shift from the signal input, it

is also used for the purposes of obtaining this phase shift in order to provide means for algebraic addition.

The quantity $-Tf3$ obtained as described, is converted into $+Tf3$ by a network 14 and amplified in the amplifier 15, for the purpose to be described.

A further input into the adding network 12 is the electrical quantity $Tf5$. Since this quantity is available from the computer of the 5" gun as a mechanical quantity, this quantity is converted into an electrical quantity by a potentiometer 16 for transmission to the adding network 12.

Another input into the adding network 12 is the quantity $Tf3 \times IV3$. For obtaining this quantity, the crank 10 is set periodically, as for example, each day according to the value of $IV3$ obtained from the ballistic tables for the number of rounds of ammunition already fired. This quantity $IV3$ so obtained is fed as a mechanical quantity into a potentiometer 17 having as an electrical input the quantity $Tf3$ obtained as described from the output of the combination 14, 15. The electrical output $Tf3 \times IV3$ obtained thereby from the potentiometer is fed as an input into the adding network 12.

Another input into the adding network 12 is the quantity $-Tf3 \times IV5$. For that purpose, the electrical quantity $-Tf3$ from the unit 12, 13 is transmitted to a potentiometer 18 receiving also the mechanical input $IV5$, to produce the electrical output $-Tf3 \times IV5$ which is transmitted to the adding network 12 as an input.

The input quantities $-Tf3 \times IV5$, $f''(Tf5)$, $Tf5$, $Tf3 \times IV3$ and $-Tf3$ (feedback from the output of the amplifier 13), when multiplied by the appropriate coefficients and combined with the appropriate constants in the adding network 12 in accordance with Equation 12 are algebraically added to produce the quantity $-Tf3$.

The quantity to be determined in the mechanization of Equation 1 is $\Delta Vm + \Delta Vfn$. One of the quantities necessary to obtain this sum of ΔVm and ΔVfn is $f''(Tf5)$ as indicated in Equation 5. The value of $f''(Tf5)$ is indicated in the graph of FIG. 2 for the different values of $Tf5$. This quantity $f''(Tf5)$ has an approximately constant relationship to the quantity $f''(Tf5)$ obtained from the potentiometer 11, and the electrical output from this potentiometer may be multiplied by a constant in a multiplying network 20 to obtain the quantity $f''(Tf5)$ as shown, or if desired, another potentiometer with the windings arranged in accordance with the relationship $f''(Tf5)$ may be provided to obtain the electrical quantity $f''(Tf5)$. This quantity $f''(Tf5)$ so obtained is transmitted to an adding network 21 as an input.

Other inputs into the adding network 21 are the electrical quantity $Tf5$ obtained from the output of the potentiometer 16 and the quantity $-Tf3 \times IV5$ obtained from the output of the potentiometers 18.

The three inputs $Tf5$, $f''(Tf5)$ and $-Tf3 \times IV5$, combined with appropriate coefficients and constants in accordance with Equations 3 and 5 in the adding network 21 result in the electrical quantity

$$-\frac{\Delta Vfn + \Delta Vm}{\cos(E2+L)}$$

which is amplified by the amplifier 22. This amplified electrical quantity is transmitted to a resolver 23 as an input in conjunction with the mechanical quantity $E2+L$ obtained for the computer of the 5" gun. The resolver 23 produces $\cos(E2+L)$ and has a potentiometer or multiplier therein to multiply this quantity by the quantity

$$-\frac{\Delta Vfn + \Delta Vm}{\cos(E2+L)}$$

to obtain the electrical output $\Delta Vfn + \Delta Vm$. This electrical output is transmitted to an adding network 24 as an input.

The other input into the adding network 24 is the quantity ΔVt . To obtain this quantity ΔVt , it is necessary

to determine the quantity $\Delta Tf/R2$ in accordance with Equations 6 and 6a. The quantity $Tf5/R2$ in electrical form for the purpose, is obtained from a potentiometer 26 having $Tf5/R2$ as a mechanical input obtained from the computer of the 5" gun. The electrical quantity $Tf5/R2$ so obtained is transmitted as an input to an adding network 27, which also receives as inputs the quantities $-Tf3$ and $-IV3$ and also the feedback $\Delta Tf/R2$ from the output of an amplifier 28, the electrical quantity $-IV3$ coming from a potentiometer 29 with a mechanical input $IV3$ from the crank 10. The constants and coefficients in accordance with the Equation 6a built into the adding network 27 result in the quantity $\Delta Tf/R2$. This quantity amplified by the amplifier 28 is transmitted to a potentiometer 30.

The positive quantity $\Delta Tf/R2$ is converted into the corresponding negative quantity by a network 31 and amplified by the unit 32. The negative output is transmitted to the potentiometer 30 in conjunction with the corresponding positive quantity, since the output may be either negative or positive. The mechanical input RdE from the computer of the 5" gun into the potentiometer 30 results in the electrical output ΔVt , which is transmitted to the adding network 24 in conjunction with the quantity $\Delta Vm + \Delta Vfn$ to produce the electrical output quantity $\Delta E'g$ in accordance with Equation 1. The electrical output quantity from this adding network 24 is processed through a servo mechanism 32 to obtain the corresponding quantity in mechanical form to be added to the 5" gun elevation order for transmission as a 3" gun elevation order. This servo mechanism 32 is of well known type and constitutes in effect an automotive drive which positions a mechanical load in accurate correspondence with an input without placing an appreciable load upon this input. The basic components of the servo mechanism 32 comprise a servo control 33, a servo amplifier 34, a servo motor 35 and an induction generator 36, all connected in a double loop circuit with the adding network 24. Essentially, the adding network 24 computes a voltage proportional to the error between a function of the input and a function of the output. This error voltage is converted to a frequency of 60 cycles by the servo control 33, amplified by the servo amplifier 34 and supplied to the servo motor 35 for its control. The servo motor 35 furnishes the mechanical output and drives the induction generator 36. From this induction generator 36, a voltage proportional to the output velocity is supplied to the servo control 33. After being modified by computing elements in the servo control 33, the modified voltage is combined with the error voltage to improve the operation of the servo mechanism.

The output of the servo motor 35 is the mechanical quantity $\Delta E'g$ and is branched off to a potentiometer 37 to be converted into the corresponding electrical quantity for feedback into the adding network, and is also branched off to a summing transmitter 40 to be added to the 5" gun elevation order $E'g5$ for the production of the 3" gun elevation order $E'g3$ and for the transmission thereof to the 3" gun control.

The transmitter 40 is of the type well-known in the gunfire control systems and comprises essentially of a fine differential synchro 41 and a coarse differential synchro 42 operated from the quantities $\Delta E'g$ and $E'g5$ and corrected by capacitors 43 and 44 respectively for power factors, to produce and transmit the required 3" gun elevation order $E'g3$.

The mechanization of Equation 15 for the 3" gun train order requires the determination of $\sin Zd$. This quantity may be obtained directly from the 5" gun computer, since it is utilized in connection with the 5" gun orders, or it may be obtained as shown, by feeding the angle Zd as mechanical inputs into resolvers 45 and 46 to obtain the positive electrical quantity $\sin Zd$ and the negative electri-

cal quantity $-\sin Zd$. These quantities required in opposite phases because the $\Delta E'g$ may be positive or negative and transmitted as inputs to a potentiometer 47 in conjunction with the mechanical input $\Delta E'g$, result in the electrical quantity $\Delta E'g \times \sin Zd$. This latter quantity is transmitted as an input to an adding network 48.

Also transmitted to the adding network 48 is the electrical quantity $RdBs \times \Delta Tf/R2$ obtained from the output of a potentiometer 49 having as mechanical input the quantity $RdBs$ obtained from the 5" gun computer, and the electrical inputs $-\Delta Tf/R2$ and $+\Delta Tf/R2$ obtained in the manner described. A further electrical input into the adding network 48 is the quantity $\Delta B'gr \times \cos (E+L)$. The quantity $\Delta B'gr$ obtained as a mechanical feedback from the output of a servo mechanism 50 arranged in conjunction with the adding network 48 for the purpose described in connection with the adding network 24 and the servo mechanism 32, is transmitted as an input to a potentiometer 51 in conjunction with the positive quantity

$$\cos (E2+L)$$

obtained from resolver 52 and the negative quantity

$$-\cos (E2+L)$$

obtained from the resolver 53. The resulting electrical output $\Delta' B'gr \times \cos (E2+L)$ which may be negative or positive is transmitted to the adding network 48.

The inputs $\Delta E'g \times \sin Zd$, $RdBs \times \Delta Tf/R2$ and $\Delta B'gr \times \cos (E2+L)$ into the adding network 48 combined with the appropriate parameters in accordance with Equation 15 result in the electrical output $\Delta B'gr$ which is processed through the servo mechanism 50 and converted into the corresponding mechanical quantity. The adding network 48 may be arranged in similar manner to adding network 12 referred to above. This mechanical quantity $\Delta B'gr$ added to the mechanical quantity $B'gr5$ from the 5" gun computer in a summing transmitter 54 similar to the summing transmitter 40, results in the gun train order $B'gr3$ for the 3" gun. This gun order $B'gr3$ is transmitted for the control of the 3" gun.

Also necessary for the 3" gun control is the parallax correction Ph which is the train parallax correction for a horizontal base. A synchro transmitter system with the Ph from the 5" gun computer as an input may be provided to transmit parallax correction for the horizontal distance between the director of the gunfire control system of the 5" gun and the 3" gun mount.

What is claimed is:

1. A converter for converting the gun elevation order angle $E'g$ of the computer of the gunfire control of a 5"-38 cal. gun to the corresponding gun order for a 3"-50 cal. gun, comprising means for receiving signals corresponding in magnitude to the respective quantities

55 $Tf5$ —time of projectile flight to target from 5" gun
 $Tf5/R2$ —the ratio of time of projectile flight from 5" gun to the advance range of the target

IV5—initial projectile velocity from the 5" gun

RdE —elevation rate which is the component of relative velocity of the ship on which the 5" and 3" guns are disposed and the target which is at right angles to the line of sight in the vertical plane containing the line of sight

60 $\cos (E2+L)$ —cosine of predicted target elevation angle $E2$ from the ship's deck plane on which the 5" gun is mounted plus level angle L

$\sin Zd$ —sine of cross-level angle which is the angle between the vertical plane through the line of sight and the plane perpendicular to the deck plane through the intersection of the deck plane and the vertical plane through the line of sight

70 IV3—initial velocity of 3" gun

$E'g5$ —gun elevation order angle of the 5" gun, means responsive to the input signals $Tf5$, $IV5$ and $IV3$

11

and to a signal corresponding in magnitude to the quantity $f'''(Tf5)$ for mechanizing the equation

Tf3

$$= \frac{1.0293Tf5 - .0919 + .662f'''(Tf5)}{1.0106 - .000348(2750 - IV3) + .00242(2600 - IV5)}$$

wherein

$Tf3$ = time of projectile flight to target from the 3" gun and

$$\begin{aligned} f'''(Tf5) &= .0296(Tf5 - 3) \text{ for } Tf5 > 3 < 5.25 \\ &= .1096(Tf5 - 4.64) \text{ for } Tf5 > 5.25 < 8 \\ &= .2192(Tf5 - 6.32) \text{ for } Tf5 > 8 \end{aligned}$$

for obtaining a signal corresponding to the quantity $Tf3$, means for employing the input signals $\cos(E2+L)$, IV3 and IV5, the signal $Tf3$ and a signal corresponding in magnitude to the signal $f''(Tf5)$ to mechanize and solve the equations

$$\Delta Vm = .00041Tf3 \cos(E2+L) \times (2750 - IV3) - (2600 - IV5)$$

$$\Delta Vgn = f''(Tf5) + .00639Tf5 - .00639Tf3(2600 - IV5) - .24 \cos(E2+L)$$

wherein

Δ is increment between gun order values for the 3" and 5" guns

Vm is the sight angle correction in gun elevation order angle due to change in initial velocity from 5" gun to 3" gun

Vfn is the normal sight angle which is the difference between normal gun elevation order angle and director elevation angle

and

$$\begin{aligned} f''(Tf5) &= .027(Tf5 - 3) \text{ for } Tf5 > 3 < 5.25 \\ &= .100(Tf5 - 4.64) \text{ for } Tf5 > 5.25 < 8 \\ &= .200(Tf5 - 6.32) \text{ for } Tf5 > 8 \end{aligned}$$

for obtaining the signal $\Delta Vm + \Delta fn$, means responsive to input signals IV3 and $Tf5/R2$ and the signal $Tf3$ for mechanizing the equation

$$\Delta Tf/R2 = .0000665Tf3 + .0000006(2750 - IV3) - Tf5/R2$$

wherein

$Tf/R2$ is the ratio of the time of flight of the projectile to the projectile target position to the advance range to the predicted target position and constitutes a conversion subtractor

12

to obtain the signal corresponding in magnitude to the quantity

$\Delta Tf/R2$, means responsive to the input signal RdE and the signal $\Delta Tf/R2$ for mechanizing the equation

$$5 \quad \Delta Vt = 32.26RdE \times \Delta Tf/R2$$

wherein

Vt is the sight angle correction due to elevation rate RdE

10 to obtain the signal corresponding in magnitude to the quantity ΔVt , means for adding the signal $\Delta Vm + \Delta fn$ and the signal ΔVt in accordance with the equation

$$\Delta E'g = \Delta Vm + \Delta fn + \Delta Vt$$

15 to obtain a signal corresponding to the quantity $\Delta E'g$, and means for adding said signal $\Delta E'g$ to a signal corresponding to the quantity $E'g$ representing the elevation order angle to the 5" gun to produce the elevation order angle for the 3" gun and means for transmitting the latter order angle for control of the 3" gun.

20 2. A converter as described in claim 1, comprising means for receiving signals corresponding in magnitude to the respective quantities

$RdBs$ —bearing rate of ship on which the 5"-38 cal. gun and the 3"-50 cal. gun are mounted and target

$\sin Zd$ —sine of cross-level angle, means responsive to the signals $RdBs$, $\sin Zd$, $\Delta Tf/R2$, $\cos(E2+L)$ and $\Delta E'g$ for obtaining a signal corresponding in magnitude to the train order angle quantity $\Delta B'gr$ in accordance with the relationship

$$\Delta B'gr = [32.26RdBs \times \Delta Tf/R2$$

$$35 \quad + 1.22 \sin Zd \Delta E'g] \frac{1}{\cos(E2+L)}$$

and means for adding the signal $\Delta B'gr$ to a signal $B'gr$ corresponding in magnitude to the train order angle for the 5" gun to produce the train order angle for the 3" gun and for transmitting the latter order angle for control of the 3" gun.
